POWDER DISPENSER

Einar L. Sovad and Arthur W. Schneuer,
St. Paul, Minn.

Application July 30, 1937, Serial No. 156,524

2 Claims. (Cl. 221—62)

Our invention relates to dispensing device particularly adaptable and designed for dispensing tooth powder.

The main object is to provide a highly efficient, inexpensive and easily operated device to be mounted in any accessible place, as in a bath room, and further to provide means for releasing variable quantities of powder directly on the bristles of a tooth brush without contact of the hand or fingers, said means of extremely simple construction and involving only two moving parts. Other objects, advantages of use and the preferred construction are hereinafter fully set forth, reference being had to the accompanying drawing, in which—

Fig. 1 is a top view of our dispensing device attached to a wall the receptacle lid being omitted.

Fig. 2 is a front view of the device.

Fig. 3 is a partly sectional right side elevation of Fig. 2 and showing in section as on line 3—3 in Fig. 2 the parts of the device forward of its wall plate.

Fig. 4 is a bottom view of Fig. 3 showing the powder release slide in open or releasing position.

Referring to the drawing by reference numerals, like characters designating corresponding parts in the various views, the preferred embodiment of our device includes first a wall plate 5 with a number of countersunk holes 6 by means of which the plate may be secured as with screws 7 onto a wall 8 or other vertical surface.

9 is an upright, preferably cylindrical powder receptacle, retained in parallel spaced relation to the plate 5 by means of a connecting main horizontal web 10 at or near the lower end of the receptacle. 11 is an upper two-part web parallel to web 10 both parts in horizontal plane and extending from the opposite sides of the receptacle to the wall plate, the outer edge parts provided with notches 11N.

Said notched parts are of such shape as to permit hanging of a tooth brush in each as is well known in the art.

9C designates any suitable type of cap for the receptacle 9 and which may be readily removed for the purpose of pouring a quantity of tooth powder into the receptacle (see Fig. 3). The lower end of the cylinder is tapered as 9T to a central outlet 13 which delivers powder directly into a reciprocable powder receiving and delivering valve which will now be described.

The powder measuring and delivering means includes an elongated, fixed, horizontal tube 14 preferably quadrangular in cross section and is integral of the lower end part 9T of the receptacle 55 and extends in a plane at right angles to but in

spaced relation to the wall plate 5 toward which it is open but is closed at its front end, as at 14C. The outlet 13 opens downwardly into the bore of the tube 14 (see Fig. 3). Within said bore is a snugly fitting valve plate 15 reciprocable in the bore and movable by means of a downwardly projecting tongue or extension 15T extending downwardly from the open rear end of the tube. Between the rear face of said tongue and the plate 5 is interposed a helical coil spring 16 under 10 compression.

15A is a row of apertures in the plate 15 which communicate and register with outlet 13 of the receptacle as the plate is reciprocated in the bore of the tube. It will be readily understood that 15 the apertures 15A are filled with powder 12 when plate 15 is moved forward as from the dotted to the full line positions in Fig. 3. When the valve plate 15 is in rearmost position, as shown in full lines in Fig. 4 and dotted in Fig. 3, the blank front 20 part of the plate is under aperture 13 preventing discharge of powder through said aperture.

However, as the valve plate is moved rearwardly toward the wall plate the apertures 15A are exposed successively at the rear open end of the 25 tube 14 and the powder in them drops out directly onto the bristles 17B of the tooth brush 17. The latter is merely held horizontal with its brush end against the valve tongue 15T, bristles up, then pushed toward the wall plate to release the 30 powder in desired quantity, the powder dropping, as stated, directly on the bristles 17B. In Fig. 4 the valve is shown pushed back about the maximum exposing all the apertures 15A and releasing an elongated stream of powder which will drop 35 on practically the entire length of the bristle part of a brush. Releasing rearward pressure, or withdrawing the brush, the valve moves back to refilling position and the operator removes the charged brush for use in brushing and cleaning 40 teeth.

Obviously this device is of highest efficiency when an easy-pouring powder is used and the device may be used for other than tooth powders, for example, cleansers of which a relatively small 45 amount is required as on a damp or wet cloth, wash cloth or on a brush, or may be used for powder lotions for the hands.

The preferred embodiment of the device, the simple construction and the use of the device have been simultaneously disclosed in the foregoing specification. It is obvious that modifications of structure may be embodied, within the scope of the description and claims, without departing from the scope and spirit of the invention.

We claim:

1. A powder dispensing device of the class described comprising a wall plate, an upright powder receptacle rigidly fixed in spaced parallel relation to said plate, said receptacle adapted to be opened at its top end, its bottom end tapered downwardly and provided with a central outlet, valve means communicating with said outlet and including a horizontal tube integral of the bottom of the receptacle and a slide valve reciprocable in said tube, said valve movable from the communicative position to selective discharge position to release powder downwardly and in spaced relation to the receptacle outlet, said valve comprising a slide reciprocable in the bore of said tube, a downwardly directed tongue integral of said valve member, a compression coil spring interposed between said tongue and the wall plate, said valve formed with a row of vertical apertures passing under the receptacle outlet to be filled with powder, said tube open rearward-

ly and downwardly at its end nearest the wall plate to release powder from said apertures.

2. A powder receptacle and dispensing device comprising an upright receptacle provided with a downwardly directed outlet at its lower end, an elongated tubular valve housing integral of the said lower end part of the receptacle and in horizontal plane its bore communicating with the receptacle outlet, a slide valve reciprocable in said bore of the valve housing and provided with a row of apertures arranged to slide successively into communication with the receptacle outlet, a downwardly directed arm comprising an integral part of the slide and accessible for contact to move the slide valve into selective position to expose said apertures successively and discharge the contents thereof.
